RETAINER PANEL AND METHOD OF FORMING

Barton H. Ford, Omaha, Nebr., assignor, by mesne assignments, of one-half to International Paper Company, New York, N.Y., a corporation of New York, and one-half to The Stanley Works, New Britain, Conn., a corporation of Connecticut

Filed May 4, 1959, Ser. No. 810,963

1 Claim. (Cl. 160—368)

This invention relates to a retainer panel for freight vehicles, and the like, providing a barrier to the flow of materials, etc. The invention is particularly useful as a freight vehicle door closure and as a temporary type of closure or retainer panel which may be employed to prevent the escape of granular material from the vehicle.

The present application is a continuation-in-part of my copending application, Serial No. 666,296, filed June 18, 1957, now abandoned.

An object of the present invention is to provide a retainer panel and a method of forming the same for use with railway cars and other freight vehicles as a means for preventing the escape of granular material from the car and providing a restraining surface against other objects such as boxes, packages, etc. being shipped. Another object is to provide a door closure or grain door and a method of forming the same whereby the door can be fabricated in an inexpensive manner and set up and employed with a minimum of labor and effort. A further object is to provide a method and means for fabricating a grain door which lends itself to machine operations so that the door can be completely fabricated at low expense while at the same time providing a door which may be installed readily while exposing automatically the reinforcing steel straps for nailing the same to the door frame. A still further object is to provide a grain door or retainer panel which may be fabricated in one or more panels and shipped in a compact form which permits ready application to a door frame. Yet a further object is to provide a closure structure in which steel straps at the ends of the door are shielded during shipment and up to the point of installation so that no injury can occur to those handling the door, while at the same time upon application to a door frame, the steel strap ends will be readily exposed for a nailing operation.

A still further object is to provide a retainer panel in which metal straps are anchored directly against the core of a corrugated board, the outer liner of the corrugated board locking the straps in embedded relation within the core. Other specific objects and advantages will appear as the specification proceeds.

The invention is shown, in connection with a grain door as an illustrative embodiment by the accompanying drawings, in which—

Figure 1 is a perspective view of a closure applied to a railway door frame and embodying my invention; Fig. 2, a broken rear view in elevation of the closure board; Fig. 3, a vertical sectional view, the section being taken as indicated at line 3—3 of Fig. 1; Fig. 4, a greatly enlarged section of the door board, the section being indicated at line 4—4 of Fig. 2; and Fig. 5, a broken, transverse, sectional view of the board or door structure, the section being taken as indicated at line 5—5 of Fig. 2.

In the illustration given, A designates a railway car and B the door frame. It will be understood that, in general practice, a storm door is carried by the car on the outer side of the door frame. C designates a door space

2

provided by the frame B and which is to be closed by my temporary closure or door D.

The grain door D comprises a board consisting of a corrugated core 10 having an inner liner 11 bonded to the core by a glue layer 12. The outer portion of the core 10 is provided with glue 13 which bonds the outer edge of the core to an outer paper liner 14. At spaced distances between the outer liner 14 and the core 10 extend the metal straps 15 which are provided with spaced

10 nail openings 16, as shown best in Fig. 5.

The board D is preferably provided with vertical score lines 17 near the side edges of the door so that the board can be folded backwardly to provide side flaps 18, as illustrated best in Fig. 1. When the flaps 18 are 15 folded backwardly, the thin paper liner 14 tears away from the straps 15, leaving the straps 15 in position against the door frame B so that the operator can readily drive nails 19 through the straps to anchor the straps to the frame B.

20 It is important that the liner 14 tear readily away from the straps 15 and also that it tear along true lines so as to form a clean break between the flap and the straps and, to facilitate this operation, I prefer to slit the end portions of the outer liner 14 at 20, the slits terminating

25 at a spaced distance 21 from the ends of the liner. The slits 20 thus facilitate the tearing of the paper liner 14 while at the same time the unslit spaced marginal portion 21 serves to confine the paper liner about the strap ends 15 to hold them in position during shipment.

30 If desired, the inner side of the straps may be provided with a layer of oil 22 near the ends of the straps where they engage the corrugated core 10. I have found, however, that by bringing the steel straps 15 directly against the corrugated core 10, separation of the core 35 from the strap ends 15 occurs very readily because of the very short area of contact. The spaced corrugations of the core 10 engage the strap 15 over a minimum of area and thus there is little tendency for the core to stick to the strap when the flap 18 is folded back. The 40 application of a small amount of oil 22 eliminates any tendency of the strap to adhere to the core.

The door D is provided with the usual bottom flap 23 and lies against the floor 24 of the car A so as to prevent the escape of granular material below the body 45 of the door. If desired, side battens 25 may be employed and a foot or pry-board 26 and a headboard 27 may be used.

In the fabrication of the door, the liners 11 and 14 may be gummed and, with the straps 15 extending between the liner 14 and the core 10, bonded to the core in the arrangement shown best in Figs. 4 and 5. Alternatively, the core 10 may be provided with adhesive and the liners 11 and 14, with the spaced straps 15 lying between liner 14 and the core 10, brought into contact 55 continuously with the traveling core 10 to form the composite panel. However formed, the resulting composite door strip is then cut into sections to provide the doors D, and the doors D are slotted either in the original forming operation or in a subsequent operation to provide the 60 end slits 20. If desired, instead of employing slits 20 as shown, the same areas may be perforated so as to permit ready tearing of the liner 14 about the straps 15 when the flaps 18 are folded back during the nailing operation.

65 In the installation operation, the door D is placed in position, as illustrated in Fig. 1, with the flap 23 formed by a longitudinal score line near the base of the door, resting against the floor 24. The operator then draws the flap 18 forwardly to expose the straps 15, as illustrated at the left-hand side of Fig. 1, and he can then nail the straps to the door frame B. After both sides 70 of the door D have been secured to the frame B, the flaps

18 are then swung to a position over the ends of straps 15 and the side battens 25 nailed so as to confine the flaps 18 in place. It will be understood that wide-headed nails, staples or other means may be employed to secure the side flaps 18 in position.

The foregoing door structure provides important new results and advantages. During shipment, the paper liner 14 provides a protective layer about the metal straps 15 so that they cannot injure the workman or catch upon objects during shipment, etc. When installed, however, the paper liner 14 readily is released from about the straps 15 so that they are exposed in flat position against the car door frame B and may be readily nailed in place. In this operation, when the flap 18 is swung forwardly, the paper liner 14 tears evenly along the straight lines 20 to release the straps and the straps remain in their original horizontal position for the nailing step. The release is a ready release by reason of the slits and also by reason of the direct contact of each strap with a minimum of area of the core, since the strap meets the core only at the spaced bends of the core. As stated above, such release can be rendered further effective, if desired, by a film of oil applied to the strap portion adjacent the core 10.

As shown more clearly in Figs. 3 and 4, the metal strap 15, in the process of fabrication, is embedded within the core so that when the outer liner 14 is applied, the liner forms a smooth continuation over the outer surface of the metal, thus giving a finished reinforced corrugated board which is relatively smooth on both sides. It is important to note that in the process of fabrication as hereinbefore described, the simultaneous feeding of the core 10, the straps 15, and the liners 14, enable the straps to engage the core at a moment before the core is stiffened by the liners with the solidifying glue. Thus, the core is free to move under contact with the straps and before the setting of the glue and the core thus absorbs the straps to form the embedded structure shown in Figs. 3 and 4. Thus, in the finished product, the strap 15 lies embedded within the core and the core, upon the setting of the glue, is now rigidly locked between the liners 11 and 14.

Under the alternate process described, in which the glue is applied to the core, a similar result is achieved in that the core may retreat under contact with the strap and before the glue sets to anchor the liner about the core, and with the result that the strap is fastened to the core at spaced points by the glue and similarly the liners are anchored about the straps to the glue; however, since the core is free at the instant when the metal strap bears against it, the recessing or embedding of the strap is accomplished as shown in Figs. 3 and 4.

It will be seen that by the sequence of steps described above, the metal strap becomes embedded within the flexing core before the core is rendered rigid, and not only does this permit the outer panel 14 to have its outer surface aligned with the strap flush with the outer surface of the remaining portion of the panel, but also with the steel strap now embedded and confined within the core, which has now become rigid, the rigidified core serves as a means for locking the strap against vertical movement. A further important advantage is that the liner can now be bonded directly to the core at the very edges of the strap. If the strap were projected outwardly from the core without being embedded in the core, the strap would hold an extended area of the liner on either side of the strap in spaced relation to the core, giving thus an extended area of de-lamination or bond-void.

While I have shown the door D as formed in a single unitary body, it will be understood that the door may be composed of several sections which may be installed in overlapping relation.

While in the foregoing specification, I have set forth a specific structure in considerable detail for the purpose of illustrating embodiments of the invention, it will be understood that such details of structure and procedure may be varied widely by those skilled in the art without departing from the spirit of my invention.

I claim:

A retainer panel adapted for use with freight vehicles, comprising a corrugated board having a corrugated core, 30 said core being equipped with a plurality of elongated parallel flutes, a paper liner bonded to each face of said core, and a plurality of spaced-apart, elongated metal straps mounted between one of said liners and said core, each of said straps being embedded in said core and positioned in contacting relation with the flutes of said core and having the length of each strap extending transversely of the length of said flutes, said board being scored along the sides thereof parallel with the length of said flutes to provide side flaps adapted to be separated from said straps when the flaps are folded along said score lines.
